[57] CLAIM

The ornamental design for a knife or a similar article, as shown and described.

DESCRIPTION

FIG. 1 is a left side elevational view of a knife showing
my new design;
FIG. 2 is a top plan view thereof;
FIG. 3 is a right side elevational view thereof;
FIG. 4 is a top end view thereof; and
FIG. 5 is a rear end view thereof.

The blade of the knife opposite that shown in FIG. 2 is identical thereto and the handle is substantially similar with the beveled tip omitted therefrom.
